UNITED STATES PATENT OFFICE.

CLARENCE J. LUTHER, OF MILWAUKEE, WISCONSIN.

GEAR-CASING.

1,182,095.

Specification of Letters Patent. Patented May 9, 1916.

Application filed May 27, 1914. Serial No. 841,196.

To all whom it may concern:

Be it known that I, CLARENCE J. LUTHER, a citizen of the United States, residing at Milwaukee, county of Milwaukee, and State 5 of Wisconsin, have invented new and useful Improvements in Gear-Casings, of which the following is a specification.

My invention relates to improvements in gear casings with particular reference to 10 that type of casings which are employed for manually driven mechanisms for operating grinding wheels, buffing wheels, etc.

The object of my invention is to provide 15 inexpensive means for securing efficient lubrication of the working parts.

In small and cheaply made machines, such as pertain to the described class, the bearings are frequently allowed to become dry, no efficient lubricating means being employed for the reason that ordinary storage 20 lubricators would be expensive to a degree that would practically prohibit sales, by raising the price of the article considerably above that of similar articles made by others. 25 By my improvement, however, I am enabled to provide a system of intercommunicating reservoirs and ducts leading to the bearings and all arranged and organized in such a manner that the entire system may be supplied with lubrication through a single inlet 30 aperture.

In the drawings Figure 1 is a side elevation of a grinding machine in which my invention is embodied. Fig. 2 is a sectional view, drawn on line $x-x$ of Fig. 1.

Like parts are identified by the same reference characters in both views.

The casing structure illustrated in the drawings, is formed in two half members 40 A and B respectively, said members meeting on a plane transverse to the driving shaft C and driven shaft D. The plane of division also passes through the driving gear wheel E and driven pinion D', which 45 is preferably formed by cutting grooves in the shaft D to form pinion teeth with which the teeth on the driving gear wheel E are adapted to mesh.

The specific manner in which the casing 50 is divided is not essential to my invention, although it affords convenient means for arranging the oil ducts of my improved lubricating system and also provides means for fully exposing the gearing when the 55 casing members are separated. The casing member A is provided with a duct a which

leads diagonally downwardly and laterally from the inlet F. The lower end of the duct a communicates with a cylindrical bore G, which is adapted to receive the driven 60 shaft D, and at the inner end of which a pocket or cavity H is formed, which may be filled with an absorbent material, such as felt. From the bottom of this cavity H, a duct a' leads downwardly in the wall of the 65 casing to an annular pocket or cavity I surrounding the cylindrical aperture or bore, which receives the driving shaft C. This cavity I may also be filled wholly or partially with an absorbent material. 70

The casing member B is provided with an angular, laterally and downwardly extending duct b , leading from the inlet F to an annular pocket J surrounding the driven shaft D, and from the bottom of which 75 pocket an auxiliary duct b' leads downwardly to a pocket K, formed at the inner end of the bore in member B which receives the driving shaft C. These pockets J and K are also wholly or partially filled with 80 absorbent material, and it will be observed that the casing members, forming the walls of the pockets H and K, constitute integral 85 end caps covering and protecting the ends of the shafts C and D, whereby the lubricant is prevented from escaping, except in so far as it may follow the shaft C to the driving crank L or follow the shaft D to the grinding wheel M.

It will be observed that the ducts a and b 90 form an apex immediately under the inlet F, whereby the nozzle of an oil can may be manipulated in either direction to feed oil either to the duct system of the casing member A or to the duct system of the casing member B. By using absorbent material 95 in the cavities or pockets H, I, J and K, the lubricant is partially retained in these cavities and slowly feeds along the shafts to the respective bearings. 100

I claim—

1. A gear casing having a gear receiving cavity, and provided with upper and lower shaft receiving apertures in the walls of said casing, said walls also having shaft 105 receiving sockets in the wall of the casing opposite each of said apertures; the socketed and apertured portions of the casing walls being enlarged interiorly to form reservoirs for a suitable lubricant and said walls being 110 also provided with ducts leading divergently from a common inlet to the upper reservoirs

and from the upper reservoirs to the lower reservoirs.

2. A gear casing provided with a gear cavity and upper and lower shaft bearings 5 in its walls, said casing having an oil inlet in its upper portion and a system of ducts leading downwardly therefrom in both side walls of the casing to each of the shaft bearings and enlarged at the bearings to 10 form reservoirs for the lubricant adapted to retain absorbent material in contact with the shafts, whereby all of the reservoirs may be supplied with lubricant through said inlet.
- 15 3. A gear casing, comprising two separable members adapted, when assembled, to

form a gear receiving cavity, each of said members having upper and lower lubricant receiving cavities, and also having shaft receiving apertures connecting said cavities 20 transversely with each other and with the gear receiving chamber, each of said casing members being also provided with a system of ducts leading from the upper inlet to the respective cavities in such member. 25

In testimony whereof I affix my signature in the presence of two witnesses.

CLARENCE J. LUTHER.
